UNITED STATES PATENT OFFICE.

JAMES HEYWOOD, OF MANCHESTER, ENGLAND.

BUILDING-MOTION OF SLUBBING, INTERMEDIATE, AND ROVING AND LIKE FRAMES.

No. 823,531.

Specification of Letters Patent.

Patented June 19, 1906.

Application filed March 22, 1904. Serial No. 199,486.

To all whom it may concern:

Be it known that I, JAMES HEYWOOD, a subject of the King of Great Britain and Ireland, and a resident of Manchester, in the county of Lancaster, England, have invented certain new and useful Improvements in the Building-Motions of Slubbing, Intermediate, and Roving and Like Frames, of which the following is a specification.

10 This invention relates to improvements in the building-motions of slubbing, intermediate, and roving and like frames used in the processes of spinning cotton and like fiber, the object of the invention being to effect improvements in or in connection with the shortening or tapering device used in such motions in order to enable the slubbing, roving, or the like to be wound on the usual bobbins with a varying conformation.

15 My invention will be fully described with reference to the accompanying drawings, in which—

Figure 1 is a partial front elevation of so much of a slubbing-frame as is necessary to enable my invention to be understood, while Fig. 2 is an end elevation, partly in section, of the mechanism. Fig. 3 shows side elevation of modification in detail, which will be hereinafter more fully referred to.

20 In carrying out my invention, and referring more particularly to Figs. 1 to 3, *a* represents the main framing of a slubbing or like frame; *b*, the bobbin or lifting-rail; *c*, the vertical shaft of the builder-motion, having mounted thereon a rope-drum *d*, to which is connected the usual rope or chain *d'* and weight *d''*, a pinion *e* gearing into the usual rack *e'*, connected with the strap *e''* on the driving-cones *e'''* and a bevel-wheel *f*. *f'* is a short shaft upon which is mounted a bevel-wheel *f''*, in gear with the bevel-wheel *f*, and located immediately behind this bevel-wheel is a pinion *g*, gearing into a rack *g'*, known as the "shortening" or "tapering" rack, the 35 said rack being mounted in one of the oscillating cradles *h* of the builder-motion. All these parts are of ordinary construction and operate in the usual way, as will be well understood by those conversant with the art.

40 My improvements particularly relate to the rack *g'*, which in ordinary cases is provided at its extreme free end with a stud and bowl, the latter engaging with a slot of a horizontal character formed in a bracket attached 45 to the bobbin or lifting-rail. In accordance with my invention instead of the rack *g'* be-

ing formed as just described it has fixed to it at its free end a shaper-plate *h'*, which is formed with more or less tapering sides *h''*. The plate is secured to the rack by a set-screw 60 or bolt *i* and a pin *i'*, the latter passing into a hole formed in the rack.

j indicates a bracket adjustably secured by the bolt *j'* to the bobbin or lifting-rail *b*, the said plate having adjustably secured thereto 65 studs *k*, upon which are mounted bowls *k'*, free to turn on said studs, or the studs may be used without the bowls or suitable projections be formed on the plate.

In Fig. 3 the rack *g'* is extended and provided with a cross-arm *n*, while the shaper-plate *h'* is divided into separate portions or halves, both pivoted by the bolt *n'* to the rack, the outer ends of the plate being adjustably secured to the cross-arm *n* by bolts 70 *n''*, so that the said plates can be adjusted to have a greater or less angle with the rack. The tapering sides *h''* of the plates in each case may be straight or curved, as indicated in the drawings, or they may be made of any 75 other suitable conformation in accordance with the exterior shape it is desired to give the slubbing, roving, or the like on the bobbins on which it is afterward wound, as will be readily understood by those conversant 80 with the art to which my invention relates.

In operation as the bobbin or lifting-rail *b* rises and falls it carries with it the bracket *j* secured thereto, and consequently causes the bowls *k'* and studs *k* to partake of the movement given to the rail. It should be understood in addition to this that the builder-motion generally, with all its attendant parts, operates in the usual way and that during this motion the cradle *h* is oscillated so as to 90 raise or lower the right-hand end of the shortening-rack *g'*. It is after this raising or lowering, as the case may be, that my invention comes into operation. As the bobbin or lifting-rail rises or falls to the extent of its traverse one or other of the bowls *k'* comes into contact with the edge of the shaper-plate and causes the right-hand end of the rack *g'* to be raised or depressed a little more, so that the ordinary mechanism, which forms no part of 95 my invention, causes the rack through the pinion *g* to be moved longitudinally in order that at the next motion different points of the shaper-plate *h'* will come in contact with the bowls *k'*. As the shaper-plate becomes 100 wider toward its base the change of motion will occur sooner both in the up and down 105

traverse of the lifting-rail, and consequently the shortening of the layers of slubbing or roving on the bobbin will be accomplished.

What I claim as my invention, and desire 5 to secure by Letters Patent, is—

1. In a building-motion of slubbing, intermediate and roving and like frames a shortening-rack, a pivoted cradle in which said rack is mounted, a shaper-plate carried by 10 the rack, shafts and spur-gear devices for operating the rack and a bracket secured to the lifting-rail, said bracket having located thereon projections between which the shaper-plate works substantially as and for the purpose described.

2. In a building-motion of slubbing, intermediate and roving and like frames a shortening-rack, a pivoted cradle in which said rack is mounted, a shaper-plate carried by 20 the rack, means for securing said shaper-plate to the rack-shafts and spur-gear devices for operating the rack and a bracket secured to the lifting-rail, said bracket having located thereon projections between which the shaper-plate works substantially as and for the purposes described.

3. In a building-motion of slubbing, intermediate and roving and like frames a shortening-rack, a pivoted cradle in which said 25

rack is mounted, a shaper-plate carried by 30 the rack, means for securing said shaper-plate to the rack, shafts and spur-gear devices for operating the rack, a bracket secured to the lifting-rail, said bracket having located thereon adjustably-arranged studs, 35 and bowls mounted on said studs between which the shaper-plate works substantially as and for the purposes described.

4. In a building-motion of slubbing, intermediate and roving and like frames a shortening-rack, shafts and spur-gear devices for 40 operating the rack, a transverse slotted arm at one end of the rack, divided shaper-plates secured to said arm at their rear ends and pivoted to the rack at their forward ends in 45 combination with a bracket secured to the lifting-rail, said bracket having located thereon adjustably-arranged studs, bowls mounted on said studs between which the divided shaper-plate works substantially as and for 50 the purposes described.

In testimony whereof I have signed my name to this specification in the presence of two witnesses.

JAMES HEYWOOD.
